Primary Examiner — Cynthia Ramirez

(57) **CLAIM**

The ornamental design for a crane, as shown and described.

DESCRIPTION

The patent or application file contains at least one drawing executed in color. Copies of this patent or patent application publication with color drawing(s) will be provided by the Office upon request and payment of the necessary fee.

Fig. 1.1 is side elevation view of our new design for a crane, the other side view being a mirror image thereof

Fig. 1.2 is a top plan view thereof;

Fig. 1.3 is a perspective view thereof; and

Fig. 1.4 is a rear elevation view thereof.

The broken lines illustrate portions of the crane that form no part of the claimed design.
